UNITED STATES PATENT OFFICE.

ROLLIN H. WHITE, OF CLEVELAND, OHIO, ASSIGNOR TO THE WHITE SEWING MACHINE COMPANY, OF CLEVELAND, OHIO, A CORPORATION OF OHIO.

APPARATUS FOR GENERATING KEROSENE-VAPOR.

SPECIFICATION forming part of Letters Patent No. 752,137, dated February 16, 1904.

Application filed April 28, 1902. Serial No. 104,907. (No model.)

To all whom it may concern:

Be it known that I, ROLLIN H. WHITE, a citizen of the United States, residing at Cleveland, in the county of Cuyahoga and State of Ohio, have invented a certain new and useful Improvement in Apparatus for Generating Kerosene-Vapor, of which the following is a full, clear, and exact description, reference being had to the accompanying drawings.

10 The object of this invention is to practically utilize kerosene or even the heavier hydro-carbon oils, as gasolene is utilized, in the following manner—viz., by vaporizing it and consuming the vapor in a gas-burner or in an explosion-engine. Many efforts have been made with this end in view; but to the best of my knowledge and belief none of these efforts have resulted in any satisfactory degree of practical success. In my judgment the reason for this lack of practical success has been the failure to appreciate this fact—to wit, that although it requires a higher temperature to vaporize kerosene than to vaporize gasolene the kerosene-vapor will be disrupted by high 25 temperatures which will not injuriously affect gasolene-vapor. The result of this disruption by unduly high temperatures is that the apparatus into which the vapor is delivered becomes clogged up by carbon or by a sticky 30 heavy hydrocarbon. This happens in burners in which it is attempted to burn this vapor and in the explosion-chambers and cylinders of explosion-engines in which it is attempted to use it. Kerosene-vapor which has been 35 subject to too high a heat will not be perfectly consumed in either of the two places referred to. To prevent the disruption of the kerosene-vapor, it is necessary to prevent it from being overheated.

40 The present invention consists in the construction and combination of parts for vaporizing the kerosene and automatically maintaining the temperature of the vapor within safe limits.

45 The invention consists in a generator for containing the oil to be vaporized, a gas-burner for heating the generator, a valve for

controlling the flow of gas to said burner, and a thermostat arranged so as to be under the influence of the heat of the vapor in the generator, which thermostat is operatively connected with said valve. 50

It also consists in the more specific combinations of parts hereinafter described, and pointed out definitely in the claims. 55

Figure 1 is a side elevation of a device employing my invention, the thermostat, a part of the generator which contains the thermostat, and the casing of the valve which the thermostat operates being in vertical section; 60 and Fig. 2 is a vertical sectional view in the plane indicated by the bent line 2-2 of Fig. 1.

Referring to the parts by letters, A represents a generator, which may be of any suitable construction adapted to contain the kerosene to be vaporized and to be heated by a gas-burner. Preferably a generator consisting of a plurality of convolutions *a*, connected in series and arranged one above another, substantially as shown, is employed. The oil is 65 admitted to the upper convolution through an inlet-pipe *a'*, and after the generation of the vapor has been begun the oil may have to be forced into the generator against some pressure due to the pressure of the vapor in the 70 lower coils. 75

D represents a gas-burner arranged beneath the generator.

C represents the discharge-pipe of the generator, through which the vapor may be conducted to the point at which it is to be used. 80 Connected with this discharge-pipe is a branch pipe E, which leads to the burner D, wherefore the vapor generated in the generator is partly utilized for producing the heat by 85 which such vapor is generated. In this branch pipe is a valve *e*, which controls the flow of gas to the burner. In the generator, and preferably in that part thereof which will contain only the kerosene-vapor—to wit, in the 90 lowest coil, as shown—is a thermostat F. Preferably one substantially like that which is shown in my Patent No. 676,790, is employed, and the mechanism intermediate of

the expandible rod f , forming a part of the thermostat and transmitting motion from it to the valve, is substantially like that which is also shown in said patent, consisting of a bell-crank lever G , which engages a shoulder e in the valve-stem.

The thermostat, as shown, consists of a copper tube f' , which is closed at one end. The open end is tightly fitted in an opening in one side of the valve-casing. An iron rod f passes through this opening and through the copper tube, and one end thereof is rigidly fastened to the closed end of the copper tube. Owing to the difference in the coefficients of expansion of this copper tube and iron rod, it will be seen that as the heat operating upon this thermostat increases the copper tube will lengthen more than the iron rod will, and therefore the end of said rod within the valve-casing will be drawn away from the valve, permitting the valve to close.

It will be understood, of course, that other forms of thermostat may be employed and that other mechanism may be employed to transmit motion from the thermostat to the valve.

What is necessary generally to carry out my invention is to have the generator heated by a gas-burner, to have the supply of the gas to said burner regulated by a thermostat in the generator, and any construction employing the parts referred to in substantially the manner herein shown and described is intended to be included in my claims.

35 In the drawings, Fig. 1 is a side view of an apparatus embodying my invention when the lower coil of the generator and the valve-casing

are sectioned. Fig. 2 is a sectional end view on line 22 of Fig. 1.

Having described my invention, I claim—

1. The combination of a generator containing oil at all times, a gas-burner for heating the same to vaporize said oil, a valve for controlling the flow of gas to said burner, and a thermostat for controlling said valve and arranged to cause the valve to move in the closing direction to reduce the gas-supply of said burner when the heat of the generated oil-vapor reaches a predetermined maximum and to move in the opening direction as the temperature of said vapor is reduced, thereby preventing the disruption of the oil-vapor, substantially as described.

2. The combination of a generator containing at all times oil to be vaporized, and having an outlet-pipe, a gas-burner arranged beneath the generator for heating the same, a branch pipe connected with said outlet-pipe and discharging into the burner, a valve controlling the flow of gas to said burner, a thermostat in the generator, and operative connections between said thermostat and valve whereby the latter will be opened when the temperature within the generator falls below a predetermined minimum and will be allowed to close when said temperature goes above a predetermined maximum, substantially as specified.

In testimony whereof I hereunto affix my signature in the presence of two witnesses.

ROLLIN H. WHITE.
